CLAIM

The ornamental design for a USB memory, as shown and described.

DESCRIPTION

FIG. 1 is a perspective view of a universal serial bus (USB) memory showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view of USB memory shown in an example environment.

The features of the USB memory shown in broken lines in FIG. 7 form no part of the claimed design.

The features shown in broken lines in FIG. 8 show environment only and form no part of the claimed design.

1 Claim, 7 Drawing Sheets
